[57] CLAIM

The ornamental design for cap, substantially as shown and described.

DESCRIPTION

FIG. 1 is a top plan view of a cap showing my new design;

FIG. 2 is a side elevational view thereof;

FIG. 3 is a front elevational view thereof; and

FIG. 4 is a rear elevational view thereof.

The characteristic feature of my design illustrated in FIGS. 1 through 4 resides in the particular surface ornamentation representative of a multilayered cheeseburger on the crown portion of the cap of the configuration shown.
